J. V. SCHAFER

LOCK

Filed March 7, 1927

Inventor:
John V. Schaefer

By *L. L. Cragg Atty*

UNITED STATES PATENT OFFICE.

JOHN V. SCHAFER, OF BRONSON, MICHIGAN, ASSIGNOR TO HARRY A. DOUGLAS, OF BRONSON, MICHIGAN.

LOCK.

Application filed March 7, 1927. Serial No. 173,386.

My invention relates to locking structures of the class employing tumbler barrels, tumblers in the barrels, and guards surrounding the tumbler barrels and with which the tumblers are engaged to lock the tumblers and to prevent the tumbler barrels from turning, if they are mounted to turn, and from which the tumblers are separated to permit the tumbler barrels to be turned.

My invention has for its object the provision of improved means for positively throwing the tumblers into position to engage the guards when the keys that are acceptable by the tumbler barrels are withdrawn, such keys serving to move the tumblers out of engagement with said guards when the keys are inserted. The means for positively throwing the tumblers into engagement with the guards when the keys are withdrawn reside in springs. These springs are desirably coiled and have their axes arranged along the axes of the barrels. Each spring desirably has its ends in pressing engagement with adjacent tumblers, one spring end serving, when the key is withdrawn, to move one tumbler in one direction into engagement with the guard, and the other spring end serving to move the other tumbler in an opposite direction into engagement with the guard. Such springs are carried by the tumbler barrels so as to have a purchase.

The invention will be more fully explained in connection with the accompanying drawing in which Fig. 1 is a cross sectional view of the preferred embodiment of the invention on line 1—1 of Fig. 2, the key being absent; Fig. 2 is a longitudinal sectional view on line 2—2 of Fig. 1, a key being shown in dotted lines within the barrel; Fig. 3 is a cross sectional view similar to Fig. 1 with the key inserted; Fig. 4 is a longitudinal sectional view taken at right angles to the direction in which Fig. 2 is taken, the key being shown in dotted lines; and Figs. 5, 6 and 7 are cross sectional views of modifications.

The tumbler barrel 1 is preferably mounted to turn within the guard 2, the tumbler barrel having a front flange 3 which prevents rearward axial movement thereof and having a nut 4 screwed upon its rear end that serves to prevent forward axial movement of the tumbler barrel, the guard 2 being interposed between the flange 3 and the

nut 4. The tumbler barrel may be connected by any suitable means desired, such as the actuating member of an electrical switch, as is well understood. The guard 2 that embraces the tumbler barrel is formed with opposite recesses 5 that are disposed in the zone in which the various tumblers 6, 7, 8 and 9 are disposed. These tumblers extend transversely of the axis of the tumbler barrel and when this tumbler barrel is properly positioned, the operating key 10 being absent, one end of each tumbler enters one or the other of the recesses 5. When the key is inserted, the tumblers are withdrawn into the barrel and out of said recesses, whereupon the tumbler barrel may be turned.

The tumblers are arranged in pairs, the adjacent tumblers 6 and 7 constituting one pair and the adjacent tumblers 8 and 9 constituting the other pair. The tumblers are desirably spaced apart by being passed through slots that constitute radial continuations of the bore of the tumbler barrel. A coiled spring 11 is provided for each pair of tumblers to project the same in the recesses 5 when the key is withdrawn. The axes of these springs desirably extend along the axis of the tumbler barrel. One pair of tumblers 6 and 7 will be specifically considered, the further explanation of it about to be given applying to the other pair of tumblers 8 and 9. In each form of the invention except that shown in Fig. 7, the spring 11 has its end portions 11', 11'', bent to extend lengthwise of the tumblers, one spring end being received in a recess formed in the side of one tumbler and the other spring end being received in a recess formed in the side of the other tumbler, the extreme ends of the spring portions 11', 11'', engaging one end of the corresponding recess that receives it. The spring is always under tension, one end of the spring serving to press upon one tumbler of the corresponding pair in one direction and the other end of the spring serving to press upon the other tumbler of this pair in the opposite direction.

When the key is inserted the tension of the spring is increased. When the key is withdrawn, one spring end serves to press one end of one tumbler into one holding recess 5, and the other spring end serves to press the opposite end of the adjacent tumbler into the other recess 5. In the structures of

Figs. 1 to 6, lugs 12 upon the tumblers are adapted to engage the shoulders 13 upon the tumbler barrel to limit the extent to which the spring may thrust the tumblers. In the structure shown in Fig. 7 the spring portions 11', 11'', the lugs 12 and shoulders 13 are omitted and the tumbler barrel is provided with wing portions 14 which overhang the slot 15 in the tumbler barrel that receives the spring, these wing portions being spaced apart a distance less than the diameter of the coils of the spring to prevent the springs from being displaced by outward movement.

10 Changes may be made without departing from the invention.

Having thus described my invention, I claim:

1. In a lock, the combination with a key 20 receiving tumbler barrel; a guard embracing said tumbler barrel; two adjacent tumblers carried by the tumbler barrel and movable oppositely into and out of engagement with said guard and operable by a key to be withdrawn from engagement with said guard; and a single coiled spring carried by the tumbler barrel which has a slot receiving the spring and a wing portion at the slot for maintaining the spring in assembly with 25 the barrel, said spring having its ends continued, one spring end being in engagement with one tumbler and the other in engagement with the other tumbler, these spring ends pressing oppositely upon said tumblers and one spring end serving, when the key is withdrawn, to press one tumbler in one direction into engagement with the guard, and the other spring end serving to press upon the other tumbler in an opposite direction 30 also into engagement with the guard.

2. In a lock, the combination with a key receiving tumbler barrel; a guard embracing said tumbler barrel; two substantially parallel tumblers carried by the tumbler 45 barrel and movable oppositely into and out of engagement with said guard and operable by a key to be withdrawn from engagement with said guard; and a single coiled spring carried by the tumbler barrel and whose axis 50 extends along the axis of the tumbler barrel which has a slot receiving the spring and a wing portion at the slot for maintaining the spring in assembly with the barrel, said spring having its ends continued, one spring 55 end being in engagement with one tumbler and the other in engagement with the other

tumbler, these spring ends pressing oppositely upon said tumblers and one spring end serving, when the key is withdrawn, to press one tumbler in one direction into engagement with the guard, and the other spring end serving to press upon the other tumbler in an opposite direction also into engagement with the guard.

3. In a lock, the combination with a key 60 receiving tumbler barrel; a guard embracing said tumbler barrel; two substantially parallel tumblers carried by the tumbler barrel and movable oppositely into and out of engagement with said guard and operable by a key to be withdrawn from engagement with said guard; and a single coiled spring carried by the tumbler barrel which has a slot receiving the spring and a wing portion at the slot for maintaining the spring 65 in assembly with the barrel, said spring having its ends continued, one spring end being in engagement with one tumbler and the other in engagement with the other tumbler, these spring ends pressing oppositely upon said tumblers and one spring end serving, when the key is withdrawn, to press one tumbler in one direction into engagement with the guard, and the other spring end serving to press upon the other tumbler in an opposite direction also into engagement with the guard.

4. In a lock, the combination with a key receiving tumbler barrel; a guard embracing said tumbler barrel; two tumblers carried by the tumbler barrel and movable oppositely into and out of engagement with said guard and operable by a key to be withdrawn from engagement with said guard; and a single coiled spring carried by the tumbler barrel which has a slot receiving the spring and a wing portion at the slot for maintaining the spring in assembly with the barrel, said spring having its ends continued, one spring end being in engagement with one tumbler and the other in engagement with the other tumbler, these spring ends pressing oppositely upon said tumblers and one spring end serving, when the key is withdrawn, to press one tumbler in one direction into engagement with the guard, and the other spring end serving to press upon the other tumbler in an opposite direction also into engagement with the guard.

In witness whereof, I hereunto subscribe my name.

JOHN V. SCHAFER.
